UNITED STATES PATENT OFFICE.

FRIEDRICH SCHREIBER, OF BERLIN, GERMANY.

TOOTH-BRIDGE.

1,116,497.

Specification of Letters Patent. Patented Nov. 10, 1914.

Application filed February 10, 1913. Serial No. 747,422.

To all whom it may concern:

Be it known that I, FRIEDRICH SCHREIBER, dentist, a citizen of Germany, residing at Berlin, Germany, have invented new and 5 useful Improvements in Tooth-Bridges, of which the following is a specification.

This invention relates to artificial dentures in the form of bridges, employed to fill a gap in the mouth of one or more artificial 10 teeth.

The object of the present invention is to obviate as much as possible any great discomfort to the patient and to render it unnecessary to crown the natural teeth on each 15 side of the gap with gold crowns.

Broadly speaking, the present invention comprises a bridge formed in two longitudinal halves secured together and attached to the abutment teeth.

20 The invention aims at efficiently securing the bridge of the natural teeth and if desired applying its ends to the biting surface of said teeth.

The invention may employ screws or the 25 like for securing the two halves of the bridge together.

Artificial teeth employed for filling the gap in the mouth are, according to this invention, secured in any well known desirable 30 manner to the bridge. In one arrangement, this invention employs a portion of the bridge itself to form the biting surface of the artificial tooth or teeth.

In the accompanying drawings:—Figures 35 1 and 2 show a portion of a lower jaw having a tooth gap viewed from above and from the side respectively. Figs. 3 and 4 show the same views provided with one constructional form of the new tooth bridge. Fig. 5 shows 40 the separate halves of the new tooth bridge in plan view. Figs. 6 to 8 show transverse sections through various constructions of the new tooth bridge.

The new tooth bridge is composed of 45 metal and comprising two halves A, A' placed side by side in the longitudinal direction. The ends are formed as clasps B, B' to be applied sidewise on each side of the tooth gap against the adjacent natural teeth 50 C, and when necessary also upon their biting surfaces, and the bridge halves are then secured together by means of screws D or the like. The ends B, B' are so fitted to the natural teeth C, that they prevent any displacement of the bridge toward the biting surfaces or in the opposite direction and do

not injuriously affect the right bite. Corresponding to the special circumstances of each case, the halves A, A' of the tooth bridge will receive a shape such as is illustrated in Figs. 4 to 8, or of some other section. If, for instance, the section be chosen as shown in Fig. 8, then the biting surface of the artificial tooth or teeth will have no slot.

The invention is not limited to the constructions illustrated. Thus for instance the new tooth bridge can be used simultaneously for several tooth gaps which are separated by one or more natural teeth. In this case 60 it may suffice in special circumstances if the tooth bridge in addition to being attached to the natural tooth or teeth which are between the gaps, is fixed only to the natural tooth on the far side of the one gap. Consequently, the tooth bridge will support the artificial tooth or teeth requisite for the filling up of the second gap without a third point of support.

Between the gum E and the bridge supporting the artificial tooth or teeth there may be left a space (Fig. 6) which can readily be cleansed in order to prevent the accumulation of remains of food and so forth. Or the bridge may be caused to touch 80 the gum within the gap. In this case (Figs. 7 and 8) the bridge is preferably sloped off 85 from the inside underneath so that in this case also the proper cleansing of the gum E can take place.

As hereinbefore described and illustrated in the drawing, the middle part of the bridge forms itself the artificial tooth or teeth, which thus would be from gold or another noble metal. It is however also possible to employ porcelain teeth in connection 90 with the new bridge. For this purpose, the middle part of the latter is only to be made narrower, and the porcelain teeth are fixed to it in any known or special manner.

As shown in Fig. 9 of the drawing, the bridge A² is constructed in accordance with the foregoing disclosure with anchoring means, and the said bridge has porcelain teeth A³ secured to it in well known manner.

What I claim is:—

1. A metal tooth bridge comprising two halves adapted to be placed side by side in the longitudinal direction of the gum, each half having clasps at both ends fitting laterally about the abutment teeth, and means for tightening said halves together.

2. A metal tooth bridge comprising two halves adapted to be placed side by side in the longitudinal direction of the gum, each half forming itself with its middle portion the artificial teeth necessary for filling the gap and having clasps at both ends fitting laterally about the abutment teeth, and means for tightening said halves together.

3. A metal tooth bridge comprising two halves adapted to be placed side by side in the longitudinal direction of the gum, each half forming itself with its middle portion

the artificial teeth necessary for filling the gap and having clasps at both ends fitting laterally about the abutment teeth, the middle portions of the bridge halves overlapping each other, and means for tightening said halves together. 15

In testimony whereof I affix my signature in presence of two witnesses.

FRIEDRICH SCHREIBER.
